UNITED STATES PATENT OFFICE

LOUIS C. GUTMAN, OF FITCHBURG, MASSACHUSETTS, ASSIGNOR TO INDEPENDENT LOCK COMPANY, OF FITCHBURG, MASSACHUSETTS, A CORPORATION OF MASSACHUSETTS

ANTIPICK PIN TUMBLER LOCK

Application filed January 31, 1930. Serial No. 425,000.

The principal object of this invention is to provide a pin tumbler lock in a form in which the picking of the lock by ordinary methods is prevented, or so greatly retarded as to make it impractical; also to provide a construction for this purpose in a form so inexpensive that it adds practically nothing to the cost of the lock. Other objects and advantages of the invention will appear hereinafter.

Reference is to be had to the accompanying drawings, in which

Fig. 1 is a side view of the cylinder of a lock constructed in accordance with this invention, partly broken away, with portions shown in diametrical section;

Fig. 2 is a section on the line 2—2 of Fig. 1, showing the normal operation of the lock; and

Fig. 3 is a similar view showing what happens when it is attempted to pick the lock.

It is well understood that in picking a lock of this character the cylinder 10 is turned slightly by the introduction of an instrument so as to hold the tumblers 11 against the side of the slot in the casing 12 in which the tumblers pass outwardly in a radial direction. This is necessary in order to apply a little friction to keep them from slipping back and enabling the person trying to pick the lock to manipulate them so as to unlock it.

This lock is constructed in all respects in accordance with an ordinary lock of this type, with the pins 15 and tumblers 11, except that the passages or slots 13 in which the tumblers 11 work are cut out at both sides to form inclined recesses 14 large enough to receive these tumblers and having stop shoulders at a distance from the cylinder less than the length of the tumblers. The sides of these recesses can be made radial or nearly so.

Now in picking the lock it is necessary to turn the cylinder 10 by an instrument as indicated in Fig. 3, and then work in to push the tumblers 11 upwardly. In an ordinary lock they are forced to go straight up in opposition to their springs 16, but in this lock, on account of having to turn the cylinder, these tumblers will swing over, as shown in Fig. 3, and come up against the sharp shoulders 14.

Therefore they cannot be moved entirely out of the cylinder. This prevents the picking of the lock in the ordinary way at least, except by working on it a long time. It has been found in practice that instead of being able to pick the lock in less than a minute, as an expert can do ordinarily, it is either impossible to do it, or else it takes a period of hours. It is not necessary to apply the invention to all the tumblers. It is sufficient to apply it to every alternate one or even to a single one of them.

It will be noted that the two recesses 14 are located at the sides of the ordinary slots and project out circumferentially, so that the ordinary slots can be located as close together as usual, and that they are so placed that it is a very simple matter to drill them or cut them in any other way. Thus very little expense is added to the cost of the lock, and it is rendered comparatively safe, so that it can be picked only when taken to a locksmith who will have plenty of time to work on it. The opening of the lock by unauthorized persons is ordinarily prevented by the simple device.

Although I have illustrated and described only a single form of the invention I am aware of the fact that changes can be made therein by any person skilled in the art without departing from the scope of the invention as expressed in the claims. Therefore, I do not wish to be limited to the exact form shown except as set forth in the claims, but what I do claim is:

1. As an article of manufacture, a lock comprising a casing with a cylinder rotatable therein and the usual pins and tumblers in the cylinder and casing for locking the cylinder in position, of stops in the casing whereby when the cylinder is turned slightly, and the tumblers projecting into the cylinder raised, said tumblers will pass to one side and their outer ends be positively stopped in position against said stops.

2. As an article of manufacture, a lock of the character described comprising a casing, a rotatable cylinder therein and the usual pins and tumblers, the cylinder having a main radial slot for receiving a tumbler when it is

projected from the cylinder, and a side recess located at an angle with a shoulder at the extreme end in position to engage the end of the tumbler when swung into the side recess and prevent the tumbler being entirely withdrawn from the cylinder.

3. In a lock of the character described, the combination of a casing or frame having a radial slot, a cylinder rotatable in the casing or frame, a locking tumbler movable in the cylinder and in said slot, and a spring in the slot to hold the tumbler normally in proper position, the cylinder having a side recess on each side of the main slot for receiving the tumbler when it is attempted to pick the lock by slightly turning the cylinder, said side recess having shoulders located at a distance from the cylinder less than the length of the tumbler.

20 20. In testimony whereof I have hereunto affixed my signature.

LOUIS C. GUTMAN.
